HER ATTORNEY

UNITED STATES PATENT OFFICE.

ELIZABETH HONGLER, OF PHILADELPHIA, PENNSYLVANIA.

FASTENING DEVICE.

Application filed December 30, 1921. Serial No. 526,017.

To all whom it may concern:

Be it known that I, ELIZABETH HONGLER, a citizen of the United States, residing at Philadelphia, in the county of Philadelphia, 5 and State of Pennsylvania, have invented certain new and useful Improvements in Fastening Devices, of which the following is a specification.

One object of my invention is to provide 10 an improved fastening device in the form of a hook for co-action with an eye for fastening together portions of garments or other articles, said hook being so constructed that it can be quickly and easily sewed in place 15 and will retain its proper position even under the most severe strain.

A further object is to make my improved fastening device of a durable construction 20 which can be readily manufactured.

These objects, and other advantageous 25 ends which will be described hereinafter, I attain in the following manner, reference being had to the accompanying drawings in which

Figure 1 is a top plan view of a hook made 30 in accordance with my invention.

Figure 2 is a side elevation of the hook shown in Figure 1.

Figure 3 is an inverted plan view of said 35 hook,

Figure 4 is a perspective view of said hook,

Figure 5 is an enlarged sectional view taken on the line 5—5 of Figure 2,

Figure 6 is a top plan view showing said 40 hook in connection with an eye,

Figure 7 is a fragmentary perspective view showing a slight modification of said hook,

Figure 8 is a top plan view of the hook 45 shown in Figure 7 with a portion of the looped eye-engaging portion broken away to reveal the under structure, and

Figure 9 is an enlarged section taken on the line 9—9 of Figure 8.

Referring to the drawing and particularly 50 to Figures 1 to 6 inclusive my improved hook 10 can be made by bending a single length of wire to provide two straight approximately parallel portions 11 and 12 which are spaced apart; the end of the portion 12

being bent to provide a loop 13; the portion 11 being bent to provide a loop 14; said loop 14 being extended to provide a central part 15 which extends lengthwise between the portions 11 and 12. This portion 15 preferably includes an upwardly extending bend 55 16 directly under the eye-engaging loop 17; said eye-engaging loop being produced by continuing parts of the portions 11 and 12 upward in the form of curved ends 18 and 60 then providing a portion 19 which extends in spaced relation above the portions 11 and 12; said portion 19 being bent at 20 and preferably flattened to provide the closed end of the eye-engaging loop; it being noted that 65 the portion 18 of the eye-engaging loop serves for abutment with the part 21 of the eye 22 as shown in Figure 6 when the hook is attached to the eye for the purpose of securing portions of garments etc. together and 70 when the eye is secured to one of the portions and the hook is secured to the other of the portions of the garment.

The part 15 after extending upward to provide the bend 16 then continues downward and has a projecting part 23 on the level with the portions 11 and 12; said projecting part extending beyond the portion 18 of the eye-engaging loop. This projecting part 23 is bent upward as shown at 24 75 and at its upper end has an enlargement or head 25 which can be produced by up-setting the end of the wire out of which the hook is produced. The part 23 preferably at its top is provided with a groove 26 as shown in 80 Figures 1 to 6 inclusive or a rib 27 as shown in Figures 7 and 8. Also the portions 11 and 12 below the eye-engaging loop are provided preferably at their tops with grooves 28 as shown in Figures 1 to 6 inclusive or with 85 ribs 29 as shown in Figures 7 and 8.

In sewing the hook to a garment or other article, the stitches can extend over the portion 23 and either the grooves 26 or ribs 27 will serve as means for abutment with the 90 sewing thread to prevent lengthwise movement of the hook and said thread will also prevent the portions 11, 12 and 23 from moving in a direction away from the cloth of the garment to which it is sewed; it be- 100

ing also noted that the sewing can extend through the loop portions 13 and 14. By thus providing the parts, the portions 11, 12 and 23 cannot move so as to disrupt or alter the proper position of the portions of the hook relatively to each other or to the garment. Furthermore by providing the part 24 with the enlargement or head 25, room is provided for the sewing needle to allow the passing of the thread over the portion 23, and the part 24 in conjunction with the head also serves as means for preventing the possible slipping of the sewing thread off the end of the part 15.

With this construction, for example, a dressmaker while sewing the hook on a garment can press on the hook to firmly hold the same in position and then pass the needle and thread over the portion 23 between the part 24 and the portion 18 and securely connect this part with the thread; said construction allowing for free action to hold the hook firmly in place while sewing to the material and preventing the eye-engaging loop from slipping or shifting on the material to which it is applied. Furthermore the dressmaker if desired can sew by passing the needle under the eye-engaging loop so as to firmly tie down the portions 11 and 12 under the eye-engaging loop and the opposite end of the hook can be securely held by projecting the needle through the looped portions 13 and 14.

I have found that in any ordinary use of my improved device, owing to the provision of the portion 23 with the parts 24 and 25, it is not necessary to sew under the eye-engaging loop since the mere sewing across the portion 23 is sufficient to hold the hook end of the device to the material; it then only being necessary to sew through the loops 13 and 14 to firmly secure the device to the material. Thus by not requiring the sewing under the eye-engaging loop, when the device is in use no contact of the hook-securing thread and engaging part of the eye is possible.

I also preferably provide additional means for preventing relative movement between the parts 11, 12 and 15 and in Figures 1 to 6 inclusive, I have shown this means in the form of laterally extending lips 30 which can be pressed or drawn from the portions 11 and 12 so as to engage slightly under the portion 15 between the bent portions 16 and the part 23. This prevents the upward movement of the eye-engaging loop relatively to the portion 15 and

I have carried this same idea out in Figures 7, 8 and 9 by producing the lips 30 on the portions 15 and having them engage upper surface parts of the portions 11 and 12. Thus these lips can be made either on

the portions 11 and 12 or on the portion 15. In Figure 6, I have illustrated the eye 22 made out of a single length of wire of general horse shoe-shape in which the end portions are flattened as shown at 31 and provided with elongated single slots 32 having notches 33 spaced apart for engagement with the sewing thread and said notches will serve to prevent the thread and end portions from moving relatively to each other since the thread will engage within the notches and hold the eyelets securely in the place in which it is intended for use.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A hook of the character described including portions spaced apart and bent upward to provide an eye-engaging loop, said hook having a part extending between said first parts and having thread-engaging portions thereon serving to prevent lengthwise movement of said latter part relatively to the thread; substantially as described.

2. A hook of the character described including portions spaced apart and bent upward to provide an eye-engaging loop, said hook having a part extending between said first parts and having a portion bent upward beyond said loop, said part having a thread-engaging portion between said eye-engaging loop and said upward bent portion to prevent relative longitudinal movement between the hook and the thread; substantially as described.

3. A hook of the character described including parts spaced apart and bent upward to form an eye engaging loop and a part extending between and beyond said parts, the intermediate part being bent to form a thread engaging loop.

4. A hook of the character described including portions spaced apart and bent upward to provide an eye-engaging loop, said hook including a portion extending between said first portions; and lips serving to prevent upward movement of said eye-engaging loop relatively to said second mentioned portion; substantially as described.

5. A hook of the character described including portions spaced apart and bent upward to form an eye-engaging loop and a part extending between said portions, said part being bent upwardly to form a hump

then downwardly and upwardly to form a thread engaging parts to prevent the hook from moving longitudinally.

6. A hook of the character described including portions spaced apart and bent upward to form an eye-engaging loop and a part extending between said portions, said part being bent upwardly to form a hump then downwardly and upwardly to form a thread engaging loop, the loop having

In testimony whereof I have signed my name to this specification in the presence of two subscribing witnesses.

ELIZABETH HONGLER.
